ATTORNEY

UNITED STATES PATENT OFFICE.

CHARLES M. KOENIG, OF FARMINGDALE, NEW YORK.

COAT-HANGER.

1,244,342.

Specification of Letters Patent. Patented Oct. 23, 1917.

Application filed January 17, 1917. Serial No. 142,890.

To all whom it may concern:

Be it known that I, CHARLES M. KOENIG, a citizen of the United States, residing at Farmingdale, in the county of Nassau and 5 State of New York, have invented new and useful Improvements in Coat-Hangers, of which the following is a specification.

Broadly stated, the invention aims to provide a coat hanger of improved construction, 10 susceptible of adjustment to accommodate itself to different size garments.

In carrying out the invention the hanger is provided with means whereby the sleeves of the garment can be supported in a manner 15 to prevent wrinkling.

I further aim to provide a hanger of the above mentioned character constructed from wire, whereby the device can be manufactured and sold at a comparatively small cost, 20 however the invention resides in the construction, combination and arrangement of parts as claimed.

In the drawing forming part of this specification like numerals of reference indicate 25 similar parts in the several views and wherein:

Figure 1 is a view in elevation of a hanger constructed in accordance with the invention.

Fig. 2 is a top plan view.

Fig. 3 is a detail view of the sectional clamp.

In the production of a hanger constructed in accordance with my invention, use is preferably made of three separate and distinct strands of wire indicated at 10, 11 and 12 respectively. These strands are intertwined in the manner shown, the strands 10 and 11 being intertwined as at 13, these 35 intertwined portions being vertically disposed, while one terminal of the strand 10 terminates to provide a hook 14 by means of which the hanger in its entirety can be suspended from a nail or other suitable support.

The opposite and corresponding extremities 40 of the strands 10 and 11 are extended in horizontal planes and are intertwined as at 15 with the third strand 12, the said extremities of the strands 10 and 11, and the 45 opposite extremities of the strand 12 terminating to provide substantially U-shaped portions 16, the parallel limbs 17 of which support a clamp, the purpose of which will be hereinafter described.

Each of said clamps preferably include 55 two sections 18 and 19 respectively, while each section at opposite ends is provided with spaced pairs of grooves 20 which define openings when the respective sections of each clamp are associated. A thumb 60 screw 21 is passed through suitable openings 22 in the respective sections of the clamp, and a nut 23 when tightened upon said screw serves to hold the respective sections of the clamp associated. One pair of openings defined by the grooves 20, when the sections are associated, receive the parallel limbs 17 65 of the U-shaped portions 16, and the clamps thus supported upon said U-shaped portions. The other pair of openings of each clamp 70 receive the spaced parallel limbs of the shoulder supporting members indicated at 24. It will be noted that each of these members is formed from a single strand of wire, and bent into substantially U-shaped 75 formation, and are mounted to slide through the openings of the clamp, whereby these shoulder supporting members can be adjusted toward and away from each other, to permit of the use of the hanger with different size garments as will be readily understood. This adjustment however is made 80 subsequent to the loosening of the nut 23, and when the nut is tightened upon the screw 21 the component parts of the hanger 85 are held fixed relatively in their adjusted positions.

Loosely suspended from the outer end of the shoulder supporting member 24 is a yoke 90 25 which is suitably twisted or otherwise associated with the shoulder supporting member, the yokes 25 being adapted to be arranged within the sleeves of the garment with a view of preventing wrinkling of the latter. It is manifest, that the device constructed in accordance with the manner above described can be cheaply manufactured and sold, and that the adjustment of the shoulder supporting members can be 95 quickly accomplished as the occasion may 100 require.

While it is believed that from the foregoing description the nature and advantages of the invention will be readily apparent, I desire to have it understood that what is 105 herein shown and described constitutes the preferred embodiment of the invention to which I do not limit myself, as such changes

may be resorted to when desired as fall within the scope of what is claimed.

What is claimed is:—

1. A garment hanger comprising a plurality of wire strands intertwisted to provide an inverted substantially T-shaped member, the stem thereof terminating to provide a hook, the lateral extensions of said member terminating to provide oppositely disposed U-shaped portions, similarly shaped elements associated with said portions and unitedly defining therewith shoulder supports for the garment, said elements being slidably adjustable with respect to 10 said U-shaped portions, and means for holding said parts fixed relatively.

2. A garment hanger comprising a plurality of wire strands intertwisted to provide an inverted substantially T-shaped member, the stem thereof terminating to provide a hook, the lateral extensions of said member terminating to provide oppositely disposed U-shaped portions, similarly shaped elements disposed in juxtaposition to the 20 U-shaped portions, and unitedly defining therewith shoulder supports for the garment, a pair of clamping members, each member including grooved mating sections, which when associated provide openings through certain of which openings said elements are slidable relatively to said U-shaped portions, and said clamps serving to 30

hold said elements fixed relative to said portions.

3. A garment hanger embodying a hook-like supporting bar, lateral extensions projecting from said bar and terminating to provide U-shaped portions, similarly shaped members slidably associated with said U-shaped portions and unitedly defining therewith shoulder supports for the garment, means for holding said members fixed in adjusted position and substantially U-shaped elements suspended from the outer extremities of the shoulder supports and capable of 40 swinging movement, said elements being adapted to be positioned within the sleeves of the garment to prevent wrinkling thereof.

4. A garment hanger comprising a hook-like stem, laterally disposed extensions at one end of the stem, said extensions terminating to provide oppositely disposed U-shaped portions, similarly shaped members associated with said portions and unitedly defining therewith shoulder supporting elements, and inverted substantially U-shaped elements positioned within the sleeves of the garment to prevent wrinkling, said elements having intermediate coiled portions encircling the outer extremities of the shoulder supports and capable of swinging movement relative thereto.

In testimony whereof I affix my signature.

CHARLES M. KOENIG.
